UNITED STATES PATENT OFFICE.

FRED R. MERRILL, OF MILES CITY, MONTANA.

DESIGN FOR A REFRESHMENT BOOTH.

Application filed June 1, 1927. Serial No. 22,276. Term of patent 7 years.

To all whom it may concern:

Be it known that I, FRED R. MERRILL, a citizen of the United States, residing at Miles City, in the county of Custer and State of Montana, have invented a certain new, original, and ornamental Design for a Refreshment Booth, of which the following is a specification, reference being had to the accompanying drawing, forming a part thereof.

Fig. 1 of the drawing shows the front elevation while Fig. 2 shows a top plan view.

I claim:

The ornamental design for a refreshment booth, as shown.

In testimony whereof I affix my signature.

FRED R. MERRILL.
